WILLIAM G. THOMAS, OF CENTRALIA, PENNSYLVANIA.

Letters Patent No. 73,672, dated January 21, 1868.

IMPROVEMENT IN GAUGE-COCKS FOR BOILERS.

The Schedule referred to in these Letters Patent and making part of the same.

TO ALL WHOM IT MAY CONCERN:

Be it known that I, W. G. THOMAS, of Centralia, in the county of Columbia, and State of Pennsylvania, have invented a new and improved Gauge-Cock; and I do hereby declare that the following is a full, clear, and exact description thereof, which will enable others skilled in the art to make and use the same, reference being had to the accompanying drawings, forming part of this specification.

The drawing represents a longitudinal section through the centre of the cock.

This invention relates to an improvement in gauge-cocks for steam-boilers, and consists in the construction of the same in several removable parts, so that the certain parts which may require repair can be taken off and repaired while there is steam in the boiler.

The boiler and water are shown in red lines, and to the former is screwed the general part, A, by means of a screw-thread, b, cut on a reduced portion of the same. c is another thread, cut on the outer reduced end of the same part A, to which is screwed the part B, having a shoulder, D', fitting tightly against a similar shoulder, C, on the part A. The bore of the part A is slightly conical, and contains a valve-seat, h, fitted tightly therein. A valve-seat, a, fits the bore of the part B in a similar manner. E is a screw, provided with a valve, H, for seating into the open end of the valve-seat a, as shown. This valve H has a thread cut on its reduced end, securing the valve to the inner end of the screw E, as shown. O is an aperture for the escape of the steam or water, and opens into the bore of the part B. The valve D has a stem, s, which rests against the valve H, and the length of said stem is such that the valve D is seated only when the screw E is withdrawn to a certain distance, or the part B containing the said screw removed altogether, for cleaning or repair. The valve D then will seat, and prevent the escape of steam or water. By screwing in the screw E, the valve H seats in a, thus shutting off the escape of the steam or water. By unscrewing E, the valve H admits the steam or water to the aperture O, and the pressure of the same against valve D causes it to follow up, and keeps its stem, s, in contact with the valve H, though the said valve does not seat until the screw E is withdrawn to a greater distance than is necessary for the mere operation of trying the gauge.

I am aware that a gauge-cock has been patented by J. Broughton, (No. 51,418,) which is made in two parts, and screwed together, similarly to mine, the object being to get at the valve for grinding, when it was worn. In this gauge, the inventor contemplated the detachment of the outer part only, when there was no steam in the boiler, as it obviously could not be unscrewed for repair when there was.

My improvement provides for the removal of the outer part, B, at any time, and when there is steam in the boiler the engineer can still use the part A, and its valve, D, as a gauge-cock, for by pressing on the stem s, which will protrude from the bore of the part A when B is unscrewed, the gauge can be tried with perfect facility.

In my gauge-cock the valve D will not be likely to become worn, for it is seldom in contact with its seat. When the valve H is worn, the screw E can be removed, and the valve H refitted or substituted by a new one in a short time. The seat a can also be easily replaced by another.

Other advantages of simplicity and cheapness, combined with those before stated, render this gauge-cock a perfect and desirable attachment to all boilers, but especially those in which high-pressure steam is generated. In the western cities, the gauge-cocks become frequently choked up with dirt, and cannot, with the gauge as heretofore made, be cleaned while there is steam in the boiler.

I claim as new, and desire to secure by Letters Patent—

The combination of the screw E with the valves D and H and parts B and C, substantially as shown and described.

WILLIAM G. THOMAS.
